(57) **CLAIM**

The ornamental design for a rally cap, as shown and described.

DESCRIPTION

FIG. 1 is a side perspective view of the rally cap showing the new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken line showing a rectangle in FIGS. 1, 5, 6 and 7 is for illustrative purposes only and forms no part of the claimed design. All other broken lines represent stitching forming part of the claimed design.
